UNITED STATES PATENT OFFICE.

GEORGE MIDDLETON, OF OLNEYVILLE, RHODE ISLAND.

NON-OVERFLOWING WATER-CLOSET.

1,180,171.

Specification of Letters Patent. Patented Apr. 18, 1916.

Application filed October 19, 1915. Serial No. 56,675.

To all whom it may concern:

Be it known that I, GEORGE MIDDLETON, a citizen of the United States, residing at Olneyville, in the county of Providence and State of Rhode Island, have invented certain new and useful Improvements in Non-Overflowing Water-Closets; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in water closet bowls and consists in the provision of a siphoning means for discharging the contents of the bowl in case the trap becomes clogged.

The invention comprises various details of construction, combinations and arrangements of parts which will be hereinafter fully described, shown in the accompanying drawings and then specifically defined in the appended claim.

My invention is illustrated in the accompanying drawings, in which:

Figure 1 is a central vertical sectional view through a bowl made in accordance with my invention. Fig. 2 is a sectional view taken on line 2—2 of Fig. 1, looking in the direction of the arrows.

Reference now being had to the details of the drawings by letter, A designates a bowl having a circumferential passageway B about its upper portion which communicates

through openings C with the interior of the bowl. The bowl is provided with the usual trap D, the downwardly extending portion E of which is provided with an elongated slot F, and openings H are formed in the under wall leading into said slot and above the lower end of the portion E. Said slot, as shown in the drawings, leads down through the rear wall and has an opening I flush with the bottom of the opening K about which the pipe N connects.

In operation, in the event of paper or any foreign matter clogging up and closing the passage O at the point O', the liquid within the bowl would be siphoned off through the apertures H in the slot F. It is found in practice that the clogging of the passage O usually begins at the point O' and the temporary backing up of the water in the bowl serves as a warning that the passage is becoming clogged.

What I claim to be new is:—

In combination with a bowl having a trap, the overhanging and downwardly inclined wall of which is provided with an elongated passageway extending through the rear wall and having an opening flush with the bottom of the wall, and another opening near the lower inclined end of the trap portion of the bowl.

In testimony whereof I hereunto affix my signature in presence of two witnesses.

GEORGE MIDDLETON.
